TELEPHONE RECEIVER

Nathaniel Baldwin, East Mill Creek, Utah

Application April 23, 1941, Serial No. 390,772

6 Claims. (Cl. 179—119)

The present invention relates to telephone receivers in which the movement of a vibrating armature of magnetic material is transmitted by a link or connecting rod to a diaphragm which may be non-magnetic. The invention is particularly an improvement on my former inventions as set forth in Patents Nos. 957,403, 1,153,593, and Re. 16,887.

The object is to provide an instrument of this class which is smaller, lighter, simpler, cheaper to manufacture, more efficient, and more rugged and durable than the structures formerly disclosed.

I attain this object by a new design of pole-pieces and magnets, a new mounting of the armature in a moulded spool, a special design of diaphragm, and a new design of terminal connections.

In the drawing Fig. 1 is a rear view of the instrument with the bottom of the shell cut away; Fig. 2 is a section along the line 8, 8 of Fig. 1; Fig. 3 is a section along the line 9, 9 of Fig. 1; Fig. 4 is a section along the line 10, 10 of Fig. 1; Fig. 5 is an enlarged portion of Fig. 3; Fig. 6 is a section along the line 11, 11 of Fig. 5; and Fig. 7 is a section of the diaphragm before installation.

In the several figures of the drawing numeral 12 designates the shell or housing for the mechanism which is provided with an earpiece or cap 13. Between the edge of the shell 12 and the cap 13 is clamped the base plate 14 which is provided with a seat for the diaphragm 15 and to which the other parts of the instrument are bolted.

The spool 16, preferably made of Bakelite or other insulating material is held in place between the limbs of the U-shaped pole-pieces 17. These pole-pieces are provided with extensions at either side, and between these extensions the two magnets 18 are inserted and clamped firmly in place by bolts 19. These magnets may be made in the form of tubes through which the bolts 19 pass, or they may be made with grooves in one side as shown in the drawing, and within these grooves the bolts 19 extend from the extensions of one pole-piece through the extensions of the other polepiece and are tapped into the base-plate 14. The magnets are made of very powerful magnet steel composition and are so magnetized that the flux passes straight through the magnets from the extensions of one pole-piece to the extensions of the other, and in the same direction through both magnets. So the magnetic circuit is divided between the two

magnets and otherwise it is divided between the limbs of the polepieces.

The spool 16 containing the actuating coil 20 is held in place by the polepieces 17 and carries the vibrating armature 21. This armature is mounted within the spool 16 upon a fulcrum which I designate as a crest fulcrum to distinguish it from the suspension wire fulcrum as used in my former structures. This crest fulcrum may consist of a point or points upon which the armature oscillates, or it may consist of one or more rocker-shaped supports 22 as illustrated in the drawing; and to keep the armature and the rocker-shaped crest fulcrum in proper relative positions thin, narrow, and flexible strips of metal 23 may be sealed as with solder or any other means at one end to the armature and at the other end to the rocker-shaped fulcrum. To insure continuous contact of the armature and fulcrum a spring 24 which may also be rocker-shaped may be used within the spool so that the middle part of the spring will bear against the armature. The combined effect of the rocker-shaped spring on one side of the armature and the rocker-shaped fulcrum on the other side will be to center the armature within the spool when it is under no strain from without and to resist displacement of the armature with a force which will be very slight when the displacement is small but which will increase with the displacement much more rapidly than the displacement increases. The resulting stabilizing effect upon the armature is very desirable because normally the armature should be very easily displaced in order that the telephone might be sensitive, but as the armature approaches the pole-pieces the magnetic attraction is multiplied, and unless the resistance to displacement is also multiplied the magnetism may overcome the elastic means and bring the armature into contact with the pole-pieces and hold it there and render the instrument inoperative. The rocker-shaped fulcrum and rocker-shaped spring are safety factors. Longitudinally of the armature depressions are made in the armature to allow the rocker-shaped fulcrum 22 to bear on surfaces which lie in a plane passing through the center of the armature at the ends, said plane being central to the armature at the ends with respect to its thickness. Similarly, a depression on the reverse side of the armature allows the rocker-shaped spring 24 to bear on a surface which lies in the same plane. The result is that slight movements of the armature will not cause

it to slip on the fulcrum 22 nor on the spring 24, as it would tend to do if there were no depressions made in the armature.

With the armature so stabilized one end of it may be connected by a link or connecting rod to a diaphragm in such way that the diaphragm will not normally be under a strain and the connecting rod will push and pull on the diaphragm in its operation. If it is desirable the rocker-shaped spring 24 may be modified in shape so as to put a strain on the diaphragm, in which case the connecting rod may exert a pulsating force on the diaphragm in one direction only. The force will either be a pulsating push or a pulsating pull.

As illustrated in the drawing the rocker-shaped spring 24 is shaped so as to assist in keeping the armature in its central position, and while the diaphragm 15 is so shaped that it needs to be put under a strain to hold it in proper shape for efficient operation the balancing force against this strain is provided by the spring 25 which is seated at one end in a socket in the armature and at the other end in a socket formed in the polepiece 17.

Before installation this diaphragm 15, Fig. 7, which is made of thin corrugated metal is slightly dished in one direction, and when installed the strain produced by the counterbalancing spring 25 renders it more nearly straight and in proper position for operation. In assembling, the spring 25, properly adjusted, is put in place and then the diaphragm with link 28, washer 29, and nut 30 is put in place, and the nut 30 is screwed up until the armature 21 is centered between the polepieces. With this arrangement the diaphragm does not have to be clamped at its periphery.

The spool 16 is provided with metallic inserts 31 to which the ends of the coil 20 are soldered and the electrical connection to these inserts is made by jumpers 32 which are also connected to the spark-gap terminals 33. These spark-gap terminals are firmly bolted to the terminal block by bolts 34 and nuts 35 and the cord terminals 36 are also clamped down upon the same bolts by nuts 37. The terminal block 38 is firmly bolted to the base plate 14 by bolts 39.

A curved aperture 40 through the terminal block 38 receives the cord 41 after it enters the shell through the opening 42. The two separate conductors of the cord 42 bend over the edge of the terminal block 38 making a loop and having all necessary resistance to a pull on the cord. For this reason there is no need of a tie-string to be used in this instrument.

I claim:

1. A telephone receiver comprising an actuating coil, U-shaped pole-pieces inclosing said coil, an armature surrounded by said coil and acted upon by said polepieces and balanced upon a

crest fulcrum, a depression in said armature to receive said crest fulcrum, a diaphragm, and means to transmit the movement of said armature to said diaphragm.

5. A telephone receiver comprising an actuating coil, U-shaped polepieces surrounding said coil, an armature within said coil and actuated by said coil and acted upon by said polepieces, a crest fulcrum for said armature, a depression in said armature to receive said crest fulcrum, a spring within said coil to hold said armature in contact with said fulcrum, a diaphragm, and means to transmit the movement of said armature to said diaphragm.

10 15. 3. A telephone receiver comprising a magnet, polepieces for said magnet, an armature acted upon by said polepieces, a coil to actuate said armature, a crest fulcrum for said armature, a depression in said armature to receive said crest fulcrum, a rocker-shaped spring to hold said armature in contact with said crest fulcrum, a diaphragm, and means to transmit the movement of said armature to said diaphragm.

20 25. 4. A telephone receiver comprising a magnet, polepieces for said magnet, an armature acted upon by said polepieces, a coil surrounding said armature to actuate said armature, a rocker-shaped crest fulcrum within said coil for said armature, a depression in said armature to receive said rocker-shaped fulcrum, a diaphragm which is dished before installation and more nearly straight after installation and connected to one end of said armature, and a spring acting upon the other end of said armature and adapted 30 35 to hold the diaphragm in straighter form and to co-operate with said diaphragm to stabilize said armature.

30 35. 5. A telephone receiver comprising a magnet, an armature, an actuating coil surrounding said armature, U-shaped polepieces for said magnet and surrounding said coil and acting upon said armature, a crest fulcrum for said armature within said coil, a rocker-shaped spring within said coil to hold said armature in contact with said fulcrum, a depression in said armature to receive said rocker-shaped spring, a diaphragm, and means to transmit the movement of said armature to said diaphragm.

40 45. 6. A telephone receiver comprising a magnet, an armature, an actuating coil surrounding said armature, U-shaped polepieces for said magnet and surrounding said coil and acting upon said armature, a depression in said armature to receive said rocker-shaped crest fulcrum, a rocker-shaped spring within said coil to hold said armature in contact with said fulcrum, a depression in said armature to receive said rocker-shaped spring, a diaphragm and means to transmit the movement of said armature to said diaphragm.

50 55 60 NATHANIEL BALDWIN.
